[57] **CLAIM**

The ornamental design for a bag carrying hook, as shown and described.

DESCRIPTION

FIG. 1 is a front view of the bag carrying hook of the present invention;

FIG. 2 is a rear view of the bag carrying hook of FIG. 1;
FIG. 3 is a left side view of the bag carrying hook of FIG. 1;

FIG. 4 is a right side view of the bag carrying hook of FIG. 1;

FIG. 5 is a top view of the bag carrying hook of FIG. 1; and,
FIG. 6 is a bottom view of the bag carrying hook of FIG. 1.
The broken line showing of strap portions in FIG. 1 are for
illustrative purposes only and form no part of the claimed
design.
